CONCRETE FORM TIE HAVING FLEXIBLE THREADS AND ASSOCIATED BOLT AND METHOD OF MAKING SAID TIE

David M. Berg, 2024 Ardmore Drive, Norristown, Pa.

Filed July 5, 1963, Ser. No. 292,866

2 Claims. (Cl. 25—131)

This invention relates to a tie and an associated bolt securable to a form and more particularly to an improved tie and bolt adapted to hold together a form into which is poured concrete, and it is an object of this invention to provide an improved concrete form tie and bolt and an improved method of making the tie.

Further, this invention relates to ties which are intended to hold a pair of laterally spaced, opposed walls of a form (into which is to be poured concrete) against any tendency of the walls to move during and after the pouring of the concrete therein.

The known ties for use with such forms have threaded portions at their opposite ends into which are threaded bolts for securing the ties to the forms. Both during assembly and disassembly of the forms, with the known ties, the bolts must be rotated, in the conventional manner, to accomplish threading during assembly and to accomplish unthreading during disassembly. Such threading and unthreading are performed manually, and with the present high cost of construction labor, it is desirable to provide a tie to which the bolt can be assembled without this time consuming threading. It is, therefore, a further object of this invention to provide a tie constructed so that the bolt can be assembled thereto quickly and without the previously indicated threading.

In one embodiment of my invention the threads at the opposite ends of a tie are formed as parts of coils and the threads are flexible and resilient, the coil being formed from a strip of spring steel (or other suitable material) and supported by rods. Bolts having rounded leading noses are then inserted through holes in the forms and pushed (with a sufficient force) axially into the coils and during this insertion the bolt threads flex back and forth, permitting full lengthwise or axial entry of the bolt into the coils (until the bolt heads abut the forms), but at the end of such insertion, the coil threads prevent lengthwise retraction of the bolts. However, when it is desired to remove the bolts, they may be removed by rotating them in the unthreading direction, in the conventional unthreading manner.

The foregoing and other objects of the invention, the principles of the invention, and the best mode in which I have contemplated applying such principles will more fully appear from the following description and accompanying drawings in illustration thereof.

FIG. 1 is a view mostly in section taken at a vertical plane through a form for concrete and illustrating the improved tie and bolts in elevation;

FIG. 2 is a partial, enlarged view of the apparatus illustrated in FIG. 1 showing the right hand coil in section and a portion of the right hand bolt;

FIG. 3 is an enlarged elevation view of the right hand portion of the tie illustrated in FIG. 1;

FIG. 4 is an end view taken along the line 4—4 in FIG. 3;

FIG. 5 is a longitudinal sectional view, but further enlarged, of a portion of the structure illustrated in FIG. 2; and

FIG. 6 is a top view of a metal strip from which the coil is formed.

Referring to the drawings, a form 10 is illustrated defined by suitable flat, opposed panels or walls 12 secured to suitable vertical studs 14 and horizontal whale pieces

2

15, the walls 12 being held in spaced relation by my improved tie 16.

The tie 16 comprises 4 coextensive steel rods 18 welded in circumferential, spaced relation to each other about the 5 cylindrical, outer surfaces of helical coils 20 and 22, the coils 20 and 22 being spaced from each other and secured to the rods at the opposite ends of the rods, as illustrated in FIG. 1, and being engaged by inserts or bolts 24 and 26, respectively, which extend through suitable holes 27 in the form, the coils and holes being axially aligned.

The coils 20 and 22 are similarly constructed and the description hereinafter (for brevity) will be in terms of one coil only, the coil 22.

15 The coil 22 is formed from one continuous, long strip 30 of suitably resilient material, such as spring steel, FIG. 6, which is initially flat. The left hand portion 32 of the strip 30 is suitably deformed and bent downwardly and at a slant with the remainder or root 33, as illustrated in FIG. 5, the left hand portion becoming the coil projections or threads 32, hereinafter referred to as threads 20, after the strip 32 is helically wound to form adjacent coil turns having a suitable thread lead and depth.

The coil is wound, as illustrated in FIGS. 2 and 5, so 25 that adjacent coil turns abut. That is, as illustrated in FIG. 5, the right hand edge portion 34 of the root 33 abuts a portion of the thread 32 of the adjacent coil turn and to facilitate the flexing of the threads 32 the right hand edge portion may be chamfered, as illustrated, but 30 in any event a sufficient portion of the thread 32 remains free below the aforementioned abutment to flex back and forth, as hereinafter further referred to in more detail.

Referring to FIG. 2 there is illustrated the bolt 26 after it has been inserted into the coil 22 to its full extent and 35 FIG. 2 also illustrates the initial or rest position of the threads 32 when they restrain axial movement of the bolt 26 in the retracting direction. FIG. 5 illustrates a portion of the bolt 26 and the coil 22 during insertion of the bolt 26 at which time the force on the bolt pushing it into the coil causes the bolt threads 38, the bolt threads 38 and the coil threads 32 engaging each other at their tip portions only, to flex the coil threads 32 from the dotted position in FIG. 5 to the full line position and back and forth between these positions as the crests of the bolt 40 threads 38 pass the coil threads 32.

The bolts have threads which in cross-section have the 45 shape of an inverted V which has an included angle of less than 90° and two adjacent bolt threads together define a generally V-shaped space having an included angle of less than 90°. Further, the opposed surfaces A and B of the coil threads and bolt threads, respectively, also jointly define an included angle of less than 90°, as also do the surfaces C and D, of the coil threads and bolt threads, respectively, when the coil threads are in their 50 initial or rest position, i.e., the full line position of FIG. 2 and the dotted line position of FIG. 5. Further, the length of the coil threads 32 relative to the bolt threads is such that if axial retraction by an axial force on the bolt only is attempted, the threads 32 will tend to wedge 55 into the V-shaped space between the bolt threads.

Even if the coil threads 32 are not long enough to accomplish the aforementioned wedging, the force required to further bend the coil threads to the right (in FIG. 5) from the initial (dotted) position is greater than that to 60 flex them to the left and is such that it would be quite difficult, if not impossible, to manually retract the bolt without the use of an assist, such as a lever tool or other tool.

Further, the outside diameter of the bolt threads 38 is 65 less than the inner diameter of the inner coil root surface to provide a space between the bolt and the coil root into which the threads may flex upon insertion of the bolt.

To facilitate the flexing of the coil threads I prefer to cut the left hand margin of the strip 30 (which will form the threads 32) before the strip 30 is coiled in a manner to form spaced teeth 40 which are wider at their roots than at their tops and separated from each other by a space of the same size but inverted.

Also, to expedite the entry of the bolts into the coils, I form the bolts with well rounded noses 45 at their forward portion and the rear portion of each bolt is provided with the usual bolt head 46 under which a washer may be placed if desired. Only the forward end of the bolt is threaded, a somewhat longer length than the length of a coil, the remainder of the bolt between the head and the threaded part being unthreaded and preferably of about the same diameter as the outer diameter of the threaded part.

Preferably, the coil ties are welded to the rods so that the rods extend slightly out beyond the coils, as illustrated in FIG. 2.

While not illustrated, the projections which engage the bolts need not be in the form of threads and could simply depend from circular rings, i.e., a series of stacked washers or rings having inturned projections could be substituted for the coils. In such event, the projections would extend vertically, radially inwardly (and not on a slant). The associated bolts need then have only a series of spaced, shoulders (not threads) rounded at the top to aid in camming up the projections. The bolts could then be inserted axially and withdrawn axially by applying to the bolts forces in the proper direction sufficient to flex the projections out of restraining engagement with the shoulders. The material of the projections and their resilience would have to be such that this force, however, would have to be a greater force than is contemplated will be applied to the bolts by the form (under pressure of the concrete), as otherwise the ties would not serve any useful purpose. In this embodiment the end washer is co-terminous with the rods at one end and a sufficient number of washers are used so that at the other end no bolt shoulder is unengaged by a washer. With such an arrangement no concrete will come into engagement with the bolt shoulders, as otherwise it would be difficult to withdraw the bolt if a bolt shoulder had become embedded in concrete. It should be noted that where a threaded bolt is used, as in the prior embodiment, if concrete does engage the bolt threads, by unthreading, the bolt may be removed.

Having described my invention, I claim:

1. In a concrete form tie and bolt assembly, a plurality

of coextensive rods, two helical coils of resilient strip material secured to said rods one at each of the end portions of the rods, said coils having spaced resilient portions bent downwardly at a slant to constitute thread portions, two bolts one of which is associated with one of said coils and the other with the other of said coils, each bolt having a threaded surface defined by inverted V-shaped threads and V-shaped spaces, the coil threads and the bolt threads being so related that, when assembled, the included angle between the adjacent, opposed surfaces of one coil thread and one bolt thread is less than 90° as is also the included angle between adjacent bolt threads, the bolt thread outer diameter being less than the coil root inner diameter, whereby the bolt may be readily inserted into the associated coil by forcefully moving the bolt axially into the associated coil at which time the coil threads spring back and forth as the bolt threads enter, but a force on the bolt in the direction to retract the bolt will tend to flex the coil threads radially inward into wedging, locking engagement with the V-shape formed by adjacent bolt threads.

2. In a concrete form tie and bolt assembly, a plurality of coextensive rods, two helical coils of resilient strip material secured to said rods one at each of the end portions of the rods, said coils having spaced resilient portions bent downwardly at a slant to constitute thread portions, two bolts one of which is associated with one of said coils and the other with the other of said coils, each bolt having a threaded surface, the bolt thread outer diameter being less than the coil root inner diameter, whereby the bolt may be readily inserted into the associated coil by forcefully moving the bolt axially into the associated coil at which time the coil threads spring back and forth as the bolt threads enter, but a force on the bolt in the direction to retract the bolt will tend to flex the coil threads radially inward into locking engagement with the bolt threads.
